UNITED STATES PATENT OFFICE.

JOHN RYAN, OF COLUMBUS, OHIO.

ELECTRIC-CIRCUIT MAKING AND BREAKING DEVICE.

No. 905,933.

Specification of Letters Patent.

Patented Dec. 8, 1908.

Application filed June 8, 1907. Serial No. 377,895.

To all whom it may concern:

Be it known that I, JOHN RYAN, a citizen of the United States, residing at Columbus, in the county of Franklin and State of Ohio, 5 have invented certain new and useful Improvements in Electric-Circuit Making and Breaking Devices, of which the following is a specification.

My invention relates to an electric circuit 10 making and breaking device, and particularly to that class of circuit making and breaking devices known as sign flashers and which are employed in connection with electric signs to alternately make and break a 15 circuit to said signs.

Further objects and advantages of the invention will be set forth in the detailed description which now follows.

In the accompanying drawing: Figure 1 20 is an end elevation of a circuit making and breaking mechanism constructed in accordance with the invention, Fig. 2 is a transverse vertical section through said mechanism upon the line $x-x$ of Fig. 3 looking in 25 the direction indicated by the arrow, Fig. 3 is a plan view of said mechanism, and, Fig. 4 is a detail vertical section upon line $y-y$ of Fig. 2.

Like numerals designate corresponding 30 parts in all of the figures of the drawing.

Referring to the drawing, the numeral 5 designates a base of insulating material. Secured upon this base by screws 6, are the end members 7 of the frame, the frame being 35 completed by a longitudinally extending block of insulating material 8 which is secured to the end members 7 of the frame by screws 9.

A shaft 10 is journaled in bearings 11 of 40 the end members 7 of the frame, and carries at one end a worm wheel 12. This worm wheel meshes with a worm pinion 13 which is fast upon a transverse shaft 14. This transverse shaft has its bearing in ears 15 of 45 the end members 7 of the frame. A driving pulley 16 is secured upon the shaft 14 and power may be applied to this pulley from any desired source to drive the shaft 10 through the pinion 13 and worm wheel 12. 50 A wheel 17 having a smooth and unbroken periphery, is fast upon the shaft 10 and turns therewith.

A plurality of hangers 18 are secured to the underside of the insulating block 8 by 55 bolts 19. These bolts pass through the insulating block and have nuts 20 threaded

upon their upper ends, said nuts being adapted to clamp the ends of metallic clips 21 firmly in position against metallic plates 22 which rest upon the upper surface of the 60 block 8. One of the leads to the sign indicated at 23, is connected to each of these clips. Pivoted in the hangers 18 are a plurality of bars 24. The bar at the left hand end of the mechanism (see Fig. 3) carries a 65 contact block 25 which rests upon and slides over the periphery of the wheel 17. The remainder of the bars are provided with clamps 26 which are adapted to clamp carbon blocks 27 in position upon the ends of 70 said bars, said clamps being held in position upon said bars by screws 28. Bolts 29 pass through the bars 24 and through the insulating block 8 and have nuts 30 threaded upon their upper ends. Springs 31 bear between the underside of the insulating block 75 8 and the upper faces of the bars 24, said springs surrounding the bolts 30. Conductors 32 connect each of the bars 24 to the clips 21 except that the left hand bar in 80 Fig. 3 has no corresponding clip 21 and consequently no conductor 32. The bar 24 at the left hand end of Fig. 3 upon the contrary, is connected by a conductor 33 and clips 34 with a contact plate 35 to which one 85 of the main leads of the circuit indicated at 36 is connected.

Secured upon the shaft 10 are a plurality of radial arms 37 and these arms carry at their outer ends segments 38 which are of 90 varying length. Rotation of the shaft 10 is in the direction of the arrow a in Fig. 2 and the segments 38 are provided at their extreme ends with carbon blocks 39 which are held in position with relation to said segments, by clamps 40, said clamps being in turn held in position upon the radial arms 37 by screws 41.

As is clearly illustrated in Fig. 2, the carbon blocks 39 are provided with tongues 39' 100 which are adapted to enter between the clamps 40 and the undersides of the segments 38 to be gripped therebetween.

The downward movement of the bars 24 is limited by the heads of the bolts 29, the 105 heads of these bolts supporting the bars in such position that the segments 38 may readily ride thereunder.

The operation of the device is as follows: The leads 23 are connected to any letter, 110 lamp or combination of lamps in the sign. The circuit is completed through this circuit

breaker from the leads 23 to the bars 24 except the left hand bar 24 in Fig. 3 through the segments 38 and arms 37 to the shaft 10, through said shaft to the wheel 17, contact block 25, arm 24 to which said contact block is connected, conductor 33 and plate 35 to the main lead 36.

During the major portion of the time that the circuit is completed to any given light 10 or letter, the circuit is a metallic one as indicated at 44 in Fig. 2, but as the end of each of the segments 38 passes from under the corresponding arm 24, the carbon blocks 39 ride under the carbon blocks 27 so that 15 only the carbon completes the circuit at the conclusion of the period during which the circuit is completed. Consequently when the carbon block 39 slips past the carbon block 27 to break the circuit, the excessive flashing 20 which would result if a metallic circuit were broken in this manner, is prevented.

I am aware of the fact that circuit breakers have been employed which are provided with revolving members, but I believe I am 25 the first to employ the carbon blocks 39 and 27 in the manner set forth, whereby a "wiping" break between the two carbon blocks is had.

From the foregoing description, it will be

seen that simple and efficient means are here- 30
in provided for accomplishing the objects
of the invention, but while the elements
shown and described are well adapted to
serve the purposes for which they are in- 35
tended, it is to be understood that the in-
vention is not limited to the precise construc-
tion set forth, but includes within its pur-
view such changes as may be made within
the scope of the appended claim.

What I claim, is:

In a device of the character described the combination with a rotative shaft, of a plurality of metallic segments carried by said shaft and rotating bodily therewith, a plurality of pivoted, metallic, arms adapted to 45 ride over said segments, an insulating block to which said arms are pivoted, headed members carried by said insulating block and passing through said arms and springs encircling said headed members and bearing 50 between said arms and said block.

In testimony whereof I affix my signature
in presence of two witnesses.

JOHN RYAN
